UNITED STATES PATENT OFFICE

OTTO WITTEL, OF ROCHESTER, NEW YORK, ASSIGNOR TO EASTMAN KODAK COMPANY OF ROCHESTER, NEW YORK, A CORPORATION OF NEW YORK

FILM HOLDING STRAP

Application filed September 3, 1929. Serial No. 320,144.

This invention relates to photography and more particularly to means for holding coils of motion picture film in shape. One object of my invention is to provide a film holding strap particularly adapted for use with certain types of non-rewind motion picture apparatus. Another object of my invention is to provide a device of the class described which is adjustable and which may be frictionally held in an adjusted position for tightly holding the outer convolutions of a coil of motion picture film. Another object of my invention is to provide a strap having overlapping ends and having slidable connections between the ends and the strap, one of which is adapted to frictionally hold the ends in a set position. Another object of my invention is to provide a strap of the class described with a fixed edge or pointer and a scale which cooperates with the pointer and which is graduated into suitable units for determining the amount of film held by the strap. Other objects will appear from the following specification, and novel features being particularly pointed out in the claims at the end thereof.

Coming now to the drawings wherein like reference characters denote like parts throughout,—

Fig. 1 is a perspective view of a strap constructed in accordance with and embodying a preferred form of my invention;

Fig. 2 is a broken view of the strap shown in Fig. 1 before being assembled into a substantially circular film holder;

Fig. 3 is a detail side elevation showing the connections which hold the ends of the strap together;

Fig. 4 is an enlarged end elevation of one of the strap holding loops showing the spring fingers which are provided for forming a frictional contact with portions of the strap, and

Fig. 5 is a similar view but with the ends of the strap passed beneath the spring fingers.

While this strap is particularly adapted for use in the motion picture apparatus shown in my two following co-pending patent applications: 361,692, film winding device

for motion picture apparatus, filed May 9, 1929, and 361,693, motion picture film winding device, filed May 9, 1929, there are obviously other uses to which such a strap could be put so that I do not limit myself to a strap for use with non-rewind motion picture apparatus.

As shown in Fig. 1, the strap may comprise a metal band 1 having ends 2 and 3 which may be held in overlapping engagement by means of the metallic loops 4 and 5. Each of these loops is preferably made with a radially extending handle in the form of a flange as shown at 6 and 7. Loop 5 as best shown in Fig. 3 may be soldered at 8 to the strap 2. This loop, therefore, provides a fixed opening at 9 through which the strap may freely slide.

Loop 4 differs from loop 5 in that it is provided with a pair of spring fingers 10 as best shown in Fig. 4, these spring fingers normally lying against the base plate 11 so that when the loop 4 is attached to the strap end 3 it will provide a frictional clamp tending to hold the overlapping strap ends together. This is indicated in Fig. 5.

The spring on the fingers 10 is sufficient to permit the strap to slide therethrough, so that the ends may be made to overlap more or less by moving the handles 6 and 7. When these handles are pulled apart to cause the strap to tightly engage the outer convolution of the film coil, the coil will be firmly held against displacement.

When a strap of the type above described is used in connection with a non-rewinding device such as shown in my two above mentioned co-pending patent applications the inner convolution of a coil of film is of a fixed diameter because it is wound upon a hub of a fixed size, consequently, it is possible to provide a scale on the outside of the strap which will cooperate with one of the handles as a pointer to indicate the amount of film in the coil. Such a scale may be expressed in units of time as shown at 11 in Fig. 2 wherein the numerals at 12 indicate the number of minutes that it will take to project the film coil at a standard rate of speed.

Or if desired the scale may be graduated

into units of length, the numerals at 13 indicating the number of feet of film enclosed by the strap.

With the setting of the strap as shown in Fig. 1 by merely glancing at the pointer which consists of the straight edge 15 formed by the handle 6, it can be seen that a film coil enclosed by the strap will take approximately 13½ minutes in running through a projection machine at a normal speed or that there is approximately 340 feet of film in the coil. This is a useful feature because it enables an operator to readily calculate how long it will take to project a given amount of film and also it will enable him to readily determine how much film he has enclosed by these straps.

I may also place direction indicating arrows on the strap as shown at 14, these arrows being to indicate the direction in which the film should pass from a coil of film enclosed by the strap to a standard projecting machine.

Having thus described my invention, what I claim as new and desire to secure by Letters Patent is,

1. In a film coil holder, the combination of a substantially circular strap having overlapping ends, with means for varying the overlap of the strap ends including two loops, one attached to one end of the strap and the other attached to the other end of the strap, each loop providing a passageway for the strap, and a handle extending radially from each loop, one loop having a fixed opening through which the strap may slide freely, and the other strap being split forming two arms adapted to press upon said strap and to form a tensioning means permitting the strap to frictionally slide through the split loop when said handles are moved relative to each other to vary the size of the film coil holder.

2. In a film coil holder, the combination of a substantially circular strap having overlapping ends, with means for varying the overlapping of the strap ends including a loop and a split loop one attached to each end of the strap and each loop being provided with a passageway for the strap the loop being of such a size that the strap may slide freely therethrough and the split loop including arms adapted to normally close the loop opening but to permit a frictional sliding movement of a strap passed through the loop opening against the pressure of the spring arms whereby the film coil holder may be moved to and retained in an adjusted position by means of the slideable strap ends.

Signed at Rochester, New York, this 30th day of August, 1929.

OTTO WITTEL
